DESIGN FOR A PUSH OR FINGER PLATE FOR DOORS.

Design No. 12,376, dated August 2, 1881.

UNITED STATES PATENT OFFICE.

RODOLPHE CHRISTESEN, OF NEW BRITAIN, CONNECTICUT, ASSIGNOR TO THE RUSSELL & ERWIN MANUFACTURING COMPANY, OF SAME PLACE.

DESIGN FOR A PUSH OR FINGER PLATE FOR DOORS.

SPECIFICATION forming part of Design No. 12,376, dated August 2, 1881.

Application filed May 25, 1881. Term of patent 7 years.

To all whom it may concern:

Be it known that I, RODOLPHE CHRISTESEN, a citizen of the United States, residing at New Britain, in the county of Hartford and 5 State of Connecticut, have invented and produced a new and original Design for the Face of a Push or Finger Plate, of which the following is a specification, reference being had to the accompanying drawing or engraving forming part thereof, which represents the same in perspective.

The front of the plate is bordered by a plain ledge or border, *a*. A short distance from each end a series of transverse bars, *b*, extend 15 from border to border, while short vertical bars extend toward the border from the transverse bar nearest thereto, and a rosette is on the sunken ground between the vertical bars, as shown. A little above the middle of the 20 plate there are other transverse bars, *c*, and rising above the upper one of said bars is a semicircular ornament, *d*. This panel is filled by two other ornaments composed of rosettes and leaflets bordered by a plain ledge, as 25 shown. Above the lower series of transverse bars *b* is a branching floral ornament on a roughened ground, and above said ornament is a single transverse bar, *e*. Rising from said bar *e*, and separated from the border *a*, there 30 are double bars *f*, and the space between said double bars and the border *a* upon the sides of the plate is ornamented by squares in groups

of five, as shown, and between the two double bars, upon the middle of the plate, is an ornament representing a vase and flowering plant. 35

I claim—

1. The design for the face of a finger-plate herein shown and described, the same consisting of the plain border with the series of transverse bars near each end, and the short vertical bars extending toward the border *a*. 40

2. The design for the face of a finger-plate herein shown and described, the same consisting of the border *a*, the three series of transverse bars, the semicircular ornament *d*, and 45 the contiguous ornaments composed of rosettes and leaflets bordered by a plain ledge.

3. The design for the face of a finger-plate herein shown and described, the same consisting of the border *a*, the double bars *f*, the 50 ornamental groups of squares outside of said double bars, and the vase and flowering plant inside of or between said bars.

4. The design for the face of a finger-plate herein shown and described, the same consisting of the border *a*, the three series of transverse bars, the transverse bar *e*, the double vertical bars, and the ornaments on the several panels formed by said border and bars. 55

RODOLPHE CHRISTESEN.
